UNITED STATES PATENT OFFICE

STEPHEN P. ENRIGHT, OF PHILADELPHIA, PENNSYLVANIA

FLUSH VALVE

Application filed February 20, 1929. Serial No. 341,383.

My invention relates to new and useful improvements in a flush valve and more particularly to improvements upon such a device illustrated in my patent application filed 5 June 7, 1928, under Serial Number 283,578, and has for one of its objects to simplify the construction and so arrange the several elements relative to each other that a greater operating efficiency is obtained.

10 Another object of the invention is to provide a flush valve particularly adapted for operation in connection with water under variable pressures.

A further object of the invention is to so 15 construct the parts that the initial flow of water assists in opening the valve to its full capacity.

A still further object of the invention is to 20 provide means for holding the valve in an open position after once being fully opened, until such time as the water pressure is reduced, when the valve will be released and will close by gravity.

Another object of the invention is to 25 provide a sliding valve member of unique construction.

With these ends in view, this invention consists in the details of construction and combination of elements hereinafter set forth and 30 then specifically designated by the claims.

In order that those skilled in the art to 35 which this invention appertains may understand how to make and use the same, I will describe its construction in detail, referring by numerals to the accompanying drawings forming a part of this application, in which:—

Fig. 1, is a side elevation of a flush valve 40 constructed in accordance with my improvement showing the handle in an inoperative position and illustrating in dotted lines the position which it may assume to move the valve member into a full open position.

Fig. 2, is an end view thereof with the handle broken away.

Fig. 3, is a bottom plan view with a portion of the handle broken off.

Fig. 4, is a longitudinal sectional view 50 with some of the parts shown in elevation,

and the valve member illustrated partly in section and shown in an open position.

Fig. 5, is a longitudinal sectional view of the casing with the valve member in a closed position and the same illustrated in 55 elevation.

Fig. 6, is a top plan view of the holding member.

Fig. 7, is a top plan view of the valve member per se.

Fig. 8, is a bottom plan view thereof.

Fig. 9, is a section on the line 9—9 of Fig. 7.

Fig. 10, is a section on the line 10—10 of Fig. 7.

In carrying out the invention as herein embodied, 11 represents a union nipple which is adapted to be threaded or otherwise connected with the outlet pipe of a flush tank and said nipple includes an eccentric body 12 having therein a passageway 13 for the water flowing into the casing 14 which is connected with the union nipple by means of the union nut 15. The eccentricity of the body of this nipple provides for slight adjustments to facilitate tiling the wall 65 through which the body 12 projects as will be readily understood.

The valve casing includes a mouth 16 providing a chamber 17 within which is located the valve seat 18 and also a body 19, the center of which is below the center of its mouth and said body is adapted to be connected in any suitable manner with the water inlet of a flush bowl.

Within the body adjacent the valve seat are formed guideways 20, one on each side of the inner surface of the body, in which are slidably mounted the trunnions 21 projecting from the valve member 22.

The valve member includes a head 23 from which projects a threaded stud 24 for the reception of the valve plug or washer 25 preferably having the non-working face and its edge enclosed in a metal cup 26 against which rests a non-metallic disc 27 provided with an inwardly and downwardly beveled outer face 28, all held in place by a nut 29 having threaded engagement with the stud 24.

Projecting from the face of the head opposite the stud are two sides 30 having a gen-

eral rearward and downward formation and these sides carry the trunnions 21. The upper edges of the sides adjacent the head or between the head and trunnions carry a transverse arcuate wall 31 which I term a baffle plate and across the lower edges of said sides is a bridge 32 while a small bar 33 extends from the bridge to the head 23. About the lower portion of the head between the lower edges of the sides and projecting rearwardly from said head is a small ledge 34, which as will be hereafter more fully explained assists in guiding a current of water to the baffle plate and also assists in lifting the head of the valve member.

From the sides 30, to the rear of the bridge extend the spaced parallel rearwardly projecting legs 35 strengthened by ribs 36, and said legs terminate in a cross piece 37.

The rear edge of the bridge 32 is adapted to be engaged by a lug 38 upon the spindle 39 which is suitably journaled in the sides of the off-set 40, said sides being here shown as a plug and nut, and said spindle carries an operating handle 41.

The cross piece 37 of the valve member, when the latter is in an open position, is adapted to engage the shoulder 42 of the catch 43 pivotally mounted by means of trunnions 44 setting in bearings 45. The shoulder 42 is slightly beveled and the rear portion of the catch or that part on the side of the trunnion centers opposite said shoulder 42 is weighted, thus tending to tip the rear end of the catch downward, as shown in Fig. 5 to assist in releasing the valve member, as will be presently explained.

The operation of the device is as follows:—

As the operating handle 41 is raised from its horizontal position shown in elevation in Fig. 1 toward a vertical position, illustrated in dotted lines in said Fig. 1, the lug 38 on the spindle 39 through its coaction with the rear edge of the bridge 32 moves the valve member 22 forwardly and since the trunnions 21 are slidably mounted in the inclined guideways 20, said valve member will be elevated during said forward movement and since the flow of water through the device forces the forward end of the valve member upward, the rear portion of said valve member will be slightly tilted. As soon as the initial unseating movement has been given to the valve member, the water will begin to flow through the valve casing below the head of the valve member and the force of this flow of water impinging against the ledge 34 and then against the baffle plate 31 will assist in lifting the forward portion or head of the valve member.

At the same time the action of the water on the enclosed face 28 of the disc 27 tends to "wedge" said disc upward, thus assisting in elevating the head of the valve member.

When the valve member is open as shown in

Fig. 4, the cross piece 37 will engage the latch 43 and elevate its weighted or outer end until the line of force on the valve member, and transmitted through said valve member is below the center line of the trunnions 44 of the latch and while in this position a relatively light pressure on the head of the valve member will hold the cross piece in engagement with the shoulder 42, so that said valve member will be prevented from closing and water may flow freely through the valve casing.

As soon as pressure on the head of the valve member is relieved to such an extent that the weighted end of the latch 43 will drop down, the cross piece 37 of the valve member will be released from the shoulder 42 and said valve member will move downwardly and rearwardly due to gravity and because of the inclined arrangement of the guide ways 20. This action will cause the valve plug 25 to engage the seat 18 and shut off the flow of water.

It might be well to state at this time that due to the downwardly beveled face 28, the water will be directed toward the lower portion of the head of the valve member and the impinging of the water against the ledge 46 and the suction action created in the passage of the water over the edge thereof will tend to force the valve member forward as well as upward, while the initial flow of water will pass through the valve casing at the bottom thereof so as to readily continue the lifting action on the valve member as above set forth.

Of course I do not wish to be limited to the exact details of construction as herein shown, as these may be varied within the limits of the appended claims without departing from the spirit of my invention.

Having thus fully described my invention, what I claim as new and useful is:—

1. A flush valve comprising a casing having a valve seat therein, a valve member including a skeleton body, a head and a cross piece, trunnions carried by the body for slidably mounting the same in inclined guideways in the casing, means to temporarily latch the valve member in an open position and a valve plug on the head for coaction with the seat.

2. The structure set forth in claim 1 in combination with a disc mounted upon the head of the valve member and having a downwardly and inwardly inclined forward face.

3. A flush valve comprising a casing having the main body portion off-set relative to the entrance end, guideways in said body, a valve seat between the main body portion and its entrance, a valve member, means carried thereby for coaction with the valve seat to control the flow of water through the casing, trunnions carried by said valve member and

slidably mounted in the guideways and a latch for coaction with the valve member to hold the latter in an elevated position when the two are in engagement and pressure is applied to said valve member, said valve member being automatically disengageable from the holding means when the pressure on said valve member is relieved.

4. The structure set forth in claim 3 in combination with means to direct an initial stream of water toward the under side of the valve member, and means carried by said valve member to wedge an end thereof upwardly due to pressure of water thereagainst.

15 5. A flush valve including a casing, a valve seat adjacent the forward end of said casing, guideways within the casing to the rear of the valve seat and inclined upwardly and forwardly, a valve member including a head, a stud projected from said head, sides extending from the rear of said head and fashioned to project downwardly and rearwardly, a curved baffle plate extending between the upper edges of said sides contiguous the head,

20 25 a curved latch extending between the lower edges of said sides contiguous the head, trunnions extending from the sides for registration with the guide ways, a bridge extending between the lower edges of the sides to the rear of the trunnions, a bar connecting said bridge and the head, legs projecting rearwardly from the sides, a cross bar at the rear ends of said legs, a spindle rotatably mounted in the casing, a lug thereon for coaction with the bridge to move the valve member forward, a latch, trunnions projecting from said latch, bearings in which said trunnions are journaled, the rear end of said latch being heavier than the forward end so that said

30 35 40 rear end is normally depressed, a shoulder at the forward end of said latch for coaction with the cross bar of the valve member, a valve plug mounted on the stud of the valve member for coaction with the valve seat, a disc also mounted on said stud and having its forward face inclined inwardly and downwardly whereby action of water under pressure will wedge the head end of the valve member upward and water passing through

45 50 55 the casing and impinging on the ledge and baffle plate will also lift the head end of the valve member and cause the cross bar to depress the forward end of the latch and engage the shoulder thereof, but when the pressure on the valve member is relieved, the heavier end of the latch will fall and release the cross bar from said latch and thereafter the valve member will move by gravity until the valve plug engages the seat, and means

60 65 70 to direct the initial flow of water to the under side of the valve member.

6. In a flush valve, a casing having a valve seat therein, a valve member slidably pivoted in said casing and adapted to be tilted, a portion of said member extending on either side

axis of the pivot, means for latching one end of said member to hold the other end in open position, and a valve plug mounted on said member for coacting with said valve seat.

In testimony whereof, I have hereunto affixed my signature.

STEPHEN P. ENRIGHT.
